UNITED STATES PATENT OFFICE.

HEINRICH GOCKEL, OF NEUWIED-ON-THE-RHINE, GERMANY.

ROLLED IRON BAR.

1,422,694.

Specification of Letters Patent.

Patented July 11, 1922.

Application filed August 21, 1919. Serial No. 319,042.

To all whom it may concern:

Be it known that I, HEINRICH GOCKEL, citizen of Germany, residing at Rheinstrasse 73, Neuwied-on-the-Rhine, Germany, have 5 invented certain new and useful Improvements in Rolled Iron Bars (for which I have filed application in Germany, January 23, 1917, of which the following is a specification.

10 My invention relates to improvements in rolled iron bars of the kind usually employed as girders and building iron trussed in concrete, and it consists in a particular mode of slitting the middle-leg or stay of the bar and 15 of pulling asunder the slitted bar to an enlarged width, thereby endowing the same with an increased bearing power and, in case the improved slitting be employed with girders, to thereby obtain a better binding of the 20 concrete to the iron skeleton.

The mode of slitting the middle-leg of girder-iron and of tearing the slitted bar asunder to an increased width is well known. The particular mode of locating the slits, 25 according to my invention, essentially consists in forming said slits by alternating rows of opposite direction with relation to the axis of the bar or girder, thereby causing the same to constitute broken lines. In pulling 30 asunder a girder slitted in such a manner, triangular apertures are obtained in the iron. But by the pulling strain the oblique bars of the girder become stretched and in consequence, the pulling asunder must not be carried 35 too far, otherwise the stays will be likely to break or, at least, be considerably reduced in strength. For such reason, according to this invention, the slits are cut alternately in opposite directions and obliquely to the 40 axis of the girder, whereby the cutting line, when coherent, will form a broken line, the angle of which will take the place opposite the stay which remains in full between the ends of two parallel slits. By this means, on 45 drawing asunder the girder to an enlarged width, a girder is obtained with lozenged apertures, in which the connecting stays are but very slightly subjected to a stretching strain, though the height of the girder is 50 considerably increased. The final result is this, that a girder is obtained which gives greater bearing power combined with great lightness of weight.

A further considerable advantage of girders of such kind is obtained in employing 55 a double arrangement of slits, whereby each

slit produces a tongue, which is separated in the angle of the slit. This allows of permitting the tongues or strips of metal formed to cohere with the main stay of the girder 60 at one of their ends, while the other end may be bent outward. On bending one end to the sides of the stay alternately, one to the right side and one to the left, the rolled iron will be still better bound into the concrete. 65 For the same purpose double slits of the kind may be employed also with other arrangements of slits, for instance with straight slits as described before, cut in parallel rows.

To make my invention perfectly understood, I will now proceed in describing the same with reference to the accompanying sheet of drawings, in which—

Fig. 1 represents a cross-section of the girder employed to support a ceiling contiguous to both sides of the girder.

Fig. 2 is a side elevation of the slitted girder, showing, on the left, the structure before the slitted member is extended vertically, and, on the right, the parts in the 80 position they assume after the blank has been extended vertically.

Fig. 3 is a horizontal section and Fig. 4 a transverse vertical section of the girder.

From Fig. 2 it will be evident, that the 85 slits *i* of the rolled iron girders *a* form broken or angular lines, the angle of which is placed opposite the stay or plain portion between the ends of two angular slits of the following row of slits *i*. The said slits *i* 90 are cut in double arrangement and the two legs of each angular slit *i* are cut at a roof-shaped angle with relation to the transverse axis of the girder, the apex of the upper range of slits being directed upward, while 95 the apex of the lower range of slits is directed downwards. On pulling the girder asunder in the vertical directions, as shown on the right side of Fig. 2, the height of the girder will be increased, as shown, the two 100 parallel long sides of each slit will be torn into the triangular shape and the strips of metal *i'*, separating the slits *i*, will be straightened or stretched, the middle portion of said strips *i'*, then, will be bent outward, 105 one portion to the right and the other to the left, keeping their connection with the girder at the respective end.

Above the slits *i* I stamp from the metal tongues or strips *d*, which tongues I bend 110 out to both sides alternately, thereby allowing the concrete to pass through the holes *e*.

The said tongues or strips *d* as well as the metal strips *i* serve to improve the trussing *b* of concrete, engaged between them to support the ceiling. They intercept or take up the strains acting transversely to the length of the girder.

In Figure 1, *b* represents concrete into which the iron bar or girder is set, *h* being reinforcing bars therein. Figure 3 shows in 10 horizontal section the girder in extended position, while Figure 4 shows the disposition of the parts thereof, as seen in vertical cross section.

I claim as my invention:

15 1. An iron bar provided with a body portion slitted upon angular lines with the slits alternately disposed, and overlapped and ar-

ranged in rows inclined to the longitudinal axis of the bar.

2. A bar in accordance with claim 1 where- 20 in the slits have their intermedial connecting strips with one end connected to the main side and their outer ends bent to alternate sides.

3. A bar in accordance with claim 2 where- 25 in the apex of one row of slits is turned in one direction and that of the other row turned in the opposite direction.

In testimony whereof I affix my signature in presence of two witnesses.

HEINRICH GOCKEL.
